UNITED STATES PATENT OFFICE.

WILLIAM W. BIRNSTOCK, OF YORK, PENNSYLVANIA, ASSIGNOR TO YORK MILK MACHINERY COMPANY, OF YORK, PENNSYLVANIA, A CORPORATION OF PENNSYLVANIA.

CRATE-FEEDING MECHANISM FOR BOTTLE-WASHING MACHINES.

Application filed November 10, 1923. Serial No. 674,025.

To all whom it may concern:

Be it known that I, WILLIAM W. BIRNSTOCK, a citizen of the United States, residing at York, in the county of York and 5 State of Pennsylvania, have invented new and useful Improvements in Crate-Feeding Mechanism for Bottle-Washing Machines, of which the following is a specification.

The present invention relates to bottle 10 washing machines and analogous apparatus and more particularly to machines of the kinds suitable for washing milk bottles while such bottles are contained in crates.

The primary object of the invention is to 15 provide novel, simplified and improved means, adapted for use in such machines, for feeding or advancing the crates of bottles intermittently or step-by-step through the machine, whereby the crates of bottles are 20 successively subjected to the action of cleansing, rinsing or other washing or cleaning devices therein, the crate-feeding means provided by the present invention being simple and inexpensive in construction and operative 25 to efficiently advance the bottle containing crates through the machine in such manner that a dwell or idle period is provided following each crate-advancing operation and preceding the next crate-advancing operation, which dwell provides ample time for 30 the washing devices within the machine to act on the bottles which are positioned opposite to them and to afford the attendant ample time to place the bottle containing crates 35 in position to enter the machine preparatory to each crate-feeding operation, the advancing movement of the bottle containing crates, however, taking place rapidly.

To these and other ends, the invention consists 40 in certain improvements and combinations and arrangement of parts, all as will be hereinafter more fully described, the features of novelty being pointed out particularly in the claims at the end of the specification.

In the accompanying drawings:—

Figure 1 is a perspective view of a bottle washing machine embodying crate-advancing means constructed in accordance with 50 the present embodiment of the invention;

Figure 2 is a detail view of the crate-advancing mechanism showing the latter at the limit of its return stroke;

Figure 3 is a view similar to Figure 2

showing, by the dotted lines, the position of 55 the crate-advancing mechanism at the commencement of its crate-advancing movement and showing by the full lines the crate-advancing mechanism at the end of its crate-advancing movement;

Figure 4 is a detail view in top plan showing the means for driving the crate-advancing mechanism; and

Figure 5 represents a transverse section 65 through the receiving end of the crate-feeding table, showing the cooperative crate-advancing cross head.

Similar parts are designated by the same reference characters in the several views.

The present invention is applicable generally to bottle washing machines and analogous apparatus and more particularly to machines of the kinds used for the cleansing or washing of milk bottles, while contained in inverted position in crates, the invention 70 providing novel and improved means for feeding or advancing the bottle containing crates intermittently or step-by-step through the machine, thus positioning the bottles successively in position to be acted upon by 75 cleansing, washing and similar devices. The preferred embodiment of the invention is shown in the accompanying drawing and will be hereinafter described in detail. It 80 is to be understood, however, that the invention is not restricted to the precise construction shown, as equivalent constructions 85 are contemplated and such will be included within the scope of the claims.

In the present instance, the invention is 90 shown applied to a machine adapted for the washing of milk bottles, the machine comprising generally a suitable framework 1 which may be appropriately constructed of channel iron and angle iron members, the 95 frame supporting a feed table 2 which may extend horizontally through the machine and may be of any suitable or well known kind for guiding and supporting bottle crates in machines of this general type. Preferably the feed table comprises angle 100 iron members which extend longitudinally through the machine and serve to guide a row of crates 3 during their passage through the machine. Tanks 4 and 5 are provided in the lower portion of the machine to contain 105 suitable washing and rinsing solutions, the tank 4 which is located toward the left hand

or crate-receiving end of the machine preferably containing a suitable liquid washing solution and provided with headers 6 from which the washing solution may be injected 5 upwardly into the open mouths and around the outsides of the bottles which are supported in inverted position on grid-like bottoms of the crates 3, and similar headers 7 and 8 are provided, both of which may receive rinsing water from the tank 5 and inject the same into the open mouths and over the exteriors of the washed bottles contained in the crates positioned above these headers; 10 or the header 8 may be connected to receive steam or hot water for sterilizing the washed and rinsed bottles. A pump 9 is preferably provided which has its inlet 10 connected to receive washing solution from the tank 4 and its outlet connected to force 15 the washing solution to and through the headers 6; and a second pump 11 is preferably provided which has its inlet connected to receive rinsing water from the tank 5 and its outlet connected to force the rinsing water to and through the headers 7 and 8, or the header 7, when the header 8 is used for sterilizing purposes. The shafts of the pumps 9 and 11 are preferably aligned and connected by a suitable coupling 12 and 20 suitable means is provided for driving the pumps, as, for example, an electric motor 13 which may be connected by a coupling 14 to the adjacent pump, the pumps and motor being preferably mounted on a suitable bed 25 15 arranged alongside of the machine. Chambers 16 and 17 may be provided above the crates and the headers below them to catch the washing and rinsing solutions and to return the same to the respective tanks 30 4 and 5, and suitable doors or covers (not shown) may be provided to enclose the chambers 16 and 17, and the crates beneath them, to prevent escape of the washing and rinsing solutions to the exterior of the machine.

The crate feeding or advancing mechanism embodying the present invention is arranged at the crate-receiving end of the machine and it operates upon each bottle containing crate as the same is placed on the receiving end of the feed table to advance this crate a predetermined distance and in so doing to cause the row of bottle containing crates on the feed table to advance a step, which will bring each crate in the row into the position previously occupied by the next preceding crate in the row, and following each reTRACTING stroke of the feeding or advancing mechanism a dwell of substantial duration occurs which affords a prolonged period for the action of the cleansing and

washing devices upon the bottles contained in the crates positioned opposite to these devices and for the draining of the bottles which are shifted out of the zones of operation of the washing and rinsing devices, 70 as well as to provide ample time for the attendant to place a crate of bottles for introduction into the machine prior to each feeding operation. Preferably and as shown in the present instance the crate feeding or 75 advancing mechanism comprises a cross head 18 which may be in the form of a shaft which is mounted to reciprocate in slots 19 which are formed in the vertical sides 20 of angle irons 21, these angle irons being substantially aligned with and constituting in effect continuations of the table 2, the slots 19 being of sufficient length to enable the cross head 18 to reciprocate a distance sufficient to advance a crate, located in front of it so as to bring this crate into abutting relation with the rear end of the row of crates contained in the machine and to advance the entire row of crates a distance equal to the length of the table which is occupied by a 80 crate. Means is provided for reciprocating the cross head 18 to effect its crate-advancing stroke, to immediately retract the cross head and to then provide a relatively long dwell or idle period during which the cross head is in its retracted position, leaving the space in front of the cross head in readiness to receive a crate of bottles. The means provided by the present invention for accomplishing this result comprises a rocker which 85 consists preferably of a frame embodying side members 22 and a suitable connecting cross member 23, the side members being pivotally connected at their lower ends to the main frame 1 of the machine by a cross 90 shaft 24 which is supported by suitable brackets 25, and the opposite or upper ends of the side members 23 are formed with forwardly directed extensions 26 which, during the swinging motions of the rocker about 95 the axis of the shaft 24 as a center, swing at the outer sides of the angle irons 21. The upper portions of the side members 22 and the extensions 26 thereof are formed with substantially angular slots 27, portions 27^a of these slots being radial to the rocker shaft or pivot 24, or substantially so, and the portions 27^b of these slots being arcuate or substantially concentric with the rocker shaft 24. The ends of the cross head or shaft 18 at the outer sides of the angle irons 21 project through the slots 27 of the respective side members 22 of the rocker and may be provided at their extremities with heads 28 to abut against the outer sides of the members 22 and thereby retain the cross head or shaft from displacement.

Means is provided for swinging the rocker about the shaft 24 as an axis and through a predetermined angle. Preferably this is 130

accomplished by a pitman 29 which is pivotally connected at one end of the rocker by the cross shaft 30 and is operatively connected at its opposite end to the pin 31 of a 5 crank 32. The crank is preferably rotated with a regular motion and at a suitable speed from a shaft 33 to which the crank is fixed, and the shaft 33 may be driven from any suitable source of power. It is preferable, 10 however, to drive the rocker actuating mechanism from the shaft of the adjacent pump 9, this being accomplished, in the construction shown, by connecting a worm shaft 34 by a coupling 35 to the shaft of the adjacent 15 pump 9, the shaft 34 having a worm 36 thereon which meshes with a worm wheel 37, the latter being mounted on a shaft 38 which serves to drive a pinion 39, the latter meshing with a gear 40 fixed on the 20 crank shaft 33. A friction clutch or slip drive may be interposed between the shaft 38 and the pinion 39 to allow the shaft 38 to revolve idly and thus avoid damage to the machine, should the operator improperly introduce 25 a crate into the machine or introduce a broken or distorted crate which would cause jamming of the crates. The rocker-driving mechanism comprising the shafts 33, 34 and 38, the worm 36 and worm 30 wheel 37 and gears 39 and 40 are preferably mounted and enclosed within a casing 42 which may be mounted on the bed 15 and may contain oil or other lubricant.

The mode of operation of the crate-feeding mechanism embodying the present invention and constructed as hereinbefore described, is as follows: When the crank 32 is swung into its extreme left-hand position, as shown in Figures 1 and 2, the rocker also is in its extreme left-hand position, the cross head or shaft 18 being then fully retracted and resting in the extreme forward ends of the portions 27^b of the slots in the rocker. The space on the crate feed table in advance of the cross head is then ready to receive a crate. As the crank 32 swings toward the right, due to the revolution of the shaft 33, the pitman 29 swings the rocker toward the right, about the shaft 24 as an axis. During the first part of this swing of the rocker, the portions 27^b of the slots therein operate idly past the cross head, leaving the latter stationary in its extreme retracted position until the portions 27^a of the slots 50 reach the cross head, as indicated by the dotted lines in Figure 3, whereupon the rocker will pick up the cross head and will cause the latter to make a forward stroke in its guiding slots 19, the forward stroke of the cross head continuing until the rocker and the crank have reached the extreme right-hand position, as shown by the full lines in Figure 3. The radial portions 27^a of the slots in the rocker compensate for the rectilinear movement of the cross head and the

arcuate swing of the rocker. As the crank 32 continues to revolve, it swings toward the left, causing the rocker, in consequence, to also swing toward the left, and during this return movement of the rocker the portions 27^a of the slots therein cause the cross head or shaft 18 to retract until the junctions of the portions 27^a and 27^b of the slots are reached, as is represented by the dotted lines in Figure 3, whereupon continued rotation of the crank 32 will cause the rocker to swing to its extreme retracted position, as shown in Figure 2, and during this part of the return stroke of the rocker, the portions 27^b of the slots in the rocker operate idly 70 past the cross head, leaving the latter in its fully retracted position. From the foregoing, it will be understood that while the crank 32 is driven continuously with a regular motion and the rocker, in consequence, swings to-and-fro with a regular motion, the cross head while operating in the portions 27^a of the slots, receives a rapid forward 75 and return movement while the final portion of the return stroke of the rocker and the initial part of the following forward stroke thereof take place while the cross head is operating in the portions 27^b of the slots, and hence these portions of the return and forward strokes of the rocker are idle, in consequence of which a dwell or idle period of the cross head is provided while the cross head is in its fully retracted position. This dwell in the operation of the cross head affords ample time for the operation of the cleaning and rinsing or other washing devices upon the crates of bottles positioned opposite to them, before being advanced, so that these operations are performed thoroughly, and a substantial period of time is afforded while the cross head is in retracted position, during which period the attendant may introduce a crate of bottles for introduction into the machine, preparatory to each advancing operation of the feeding mechanism.

I claim as my invention:—

1. In a machine of the class described comprising a feed table along which a row of bottle crates is adapted to be advanced, a crate-feeding mechanism comprising a member adapted to reciprocate longitudinally of the table, and a rocker having means for imparting swinging movements to said rocker, said rocker having means which connects it with said member and which is operative to impart a crate-advancing stroke thereto and to retract said member during the to-and-fro swinging movements of the rocker toward one end of its range of movement and to provide a dwell in the operation of said member during the to-and-fro swinging movements of the rocker toward the other end of its range of movement.

2. Crate-feeding mechanism for machines

- of the class described comprising a feed table for the crates, a cross-head guided to reciprocate longitudinally thereof, and a rocker mounted to swing to-and-fro and having an operative connection toward its free end with the cross-head whereby the to-and-fro swinging movement of the rocker toward and from one end of its range of movement will cause advancing and return strokes of the cross-head and to-and-fro movements of the rocker toward and from the opposite end of its range of movement will take place while the cross-head remains idle at the end of its retracting stroke.
3. Crate feeding mechanism for machines of the class described comprising a crate-feeding table, a cross-head guided to reciprocate longitudinally thereof, and a swinging rocker having slotted portions toward its free end cooperative with the cross-head to advance and retract the cross head while the rocker is swinging toward and from one limit of its swinging movement and to allow the cross head to dwell in its retracted position while the rocker is swinging toward and from the opposite limit of its swinging movement.
4. Crate feeding mechanism for machines of the class described comprising a crate feeding table, a cross-head guided to reciprocate longitudinally thereof, and a rocker pivoted to swing relatively to the table and having an angularly-shaped slot toward its free end which cooperates with the cross-head, one portion of said slot cooperating with the cross-head, during part of the swing of the rocker, to cause crate-advancing movement of the cross-head and another portion of the slot cooperating with the cross-head during another part of the swing of the rocker, to produce a dwell in the operation of the cross head.
5. Crate advancing mechanism for machines of the class described comprising a crate feeding table, a cross head reciprocable longitudinally thereof, and a rocker pivoted to swing relatively to the table and having an angularly-shaped slot toward its free end, one portion of the slot cooperat-
- ing with the cross head, while the rocker is swinging toward and from one end of its range of movement, to impart advancing and retracting strokes to the cross head, and another portion of said slot cooperating with the cross head, while the rocker is swinging toward and from the other end of its range of movement, to cause the cross head to dwell in its retracted position.
6. Crate advancing mechanism for machines of the class described comprising a crate feeding table, a crate advancing member guided to reciprocate longitudinally thereof, and a rocker mounted to swing relatively to the table and having a slot toward its free end, a portion of which is substantially radial to the axis of movement of the rocker and another portion of which slot is substantially concentric with said axis, said slot cooperating with the crate advancing member to impart advancing and retracting movements thereto while the rocker is swinging to and fro through part of its range of movement and to cause a dwell in the operation of said member while the rocker is swinging to and fro through another part of its range of movement.
7. Crate advancing mechanism for machines of the class described comprising a crate feeding table having longitudinally extending slots in its opposite sides, a cross head extending through said slots and reciprocable longitudinally therein, a rocker comprising members pivoted to swing relatively to the table and having their free ends arranged to operate at the outer sides of the table, the free ends of said rocker members having slots which cooperate with the respective ends of the cross-head, each slot having a portion which extends substantially radially of the pivot of the rocker and another portion which extends substantially concentrically of said axis and means for imparting to-and-fro swinging movements to the rocker.
- In testimony whereof I have hereunto set my hand.

WILLIAM W. BIRNSTOCK.
